SHAFT AND RATCHET LOCKING MEANS

Victor H. Harbert, Chicago, Ill., assignor to Illinois Railway Equipment Company, Chicago, Ill., a corporation of Illinois

Application May 18, 1934, Serial No. 726,253

4 Claims. (Cl. 287—52)

My invention relates to self-locking means whereby the ratchet will be properly locked to its controlling shaft; the invention being especially intended for locking the ratchet to a brake-staff or to the operating shaft of dump cars and the like.

The invention has for its object the provision of means adapted to be disposed intermediate of the hub of the ratchet and the staff or shaft 10 and provide a self-locking relation between the ratchet and shaft while at the same time providing means which will prevent the accidental or unintentional dissociation of the respective elements; namely means which may be employed 15 with shafts of square or circular cross-section.

A further object of the invention is the provision of means of simple construction and easy application without need for special tools or skill and which is adapted to withstand the strains 20 to which it will be subjected.

The above enumerated objects as well as others and the advantages inherent in the invention will all be readily comprehended from the detailed description of the accompanying drawings, 25 wherein:—

Figure 1 is a top plan view of my improved ratchet and locking means and a transverse section of a staff.

Figure 2 is a transverse sectional view taken 30 substantially on the line 2—2 of Figure 1, with the staff in elevation.

Figure 3 is a sectional perspective view of the ratchet shown in Figure 1.

Figure 4 is a detail view in perspective of the 35 locking means employed in Figures 1 and 2.

Figure 5 is a view similar to Figure 1 showing a modification.

Figure 6 is a transverse sectional view taken 40 substantially on the line 6—6 of Figure 5, with the staff in elevation.

Figure 7 is a sectional perspective view similar to Figure 3.

Figure 8 is a detail perspective of the locking 45 means employed in Figures 5 and 6.

My invention relates to means whereby a ratchet may be locked to a shaft against independent rotation, as for example the ratchets on the shafts of drop bottom dump cars, and particularly for locking the ratchet to the brake 50 staffs of railroad cars.

These ratchets are generally cast while the shafts or staffs are more or less roughly forged. The cross-sectional dimensions of the staffs are such as to permit the staffs to be easily inserted 55 through the angular openings in the hubs of

the ratchets with possibly a clearance of approximately a sixteenth of an inch; an absolutely snug fit between the rough forged staff or shaft and the cast hub of the ratchet, therefore, not being possible. It has been found in practice 5 after comparatively short use and particularly in brake applications, that the corners of the staff soon become more or less rounded or cut providing too much play between staff and ratchet and ultimately rotation of the staff in 10 the ratchet which makes proper brake application impossible.

My invention contemplates means to be used with the usual shaft or staff and a ratchet provided with a prearranged hub-bore whereby a 15 self-locking relation between the staff and the ratchet will be provided, while at the same time accidental dissociation of the respective elements is made impossible.

In the particular embodiment of the invention 20 as illustrated in the first four figures of the drawings, the invention is disclosed as especially adapted to brake operating staffs, a portion whereof is indicated at 10; the staff 10 being angular or substantially square in cross-section. 25

These brake operating staffs are generally rough forgings without very defined or sharp corners; and the lower end of the staff has one end of a chain secured thereto whereby the usual 30 brake rigging is operated; while the upper end of the staff is provided with the usual hand wheel.

As my invention forms no part of the brake rigging—and is applicable to ratchets and shafts intended for other purposes,—illustration of the brake rigging and hand wheel is not necessary; 35 nor of the usual locking pawl whereby the ratchet 11 with the staff is held in the brake adjusting or applying position.

The ratchet 11, which so far as its general construction is concerned, may be of conventional form, is provided with a hub 12 which is shown extended somewhat to a greater extent on one side of the ratchet as indicated at 13 in Figures 2 and 3, with three walls at right angles to each other and with one side wall of the hub 45 preferably made arcuate as shown at 14 in Figure 3; while the end of the hub on the opposite side of the ratchet is preferably annular.

The hub is also enlarged or extended laterally or in a radial direction at one side of the axis, 50 namely in the direction of the arcuate wall 14, as can clearly be seen in Figures 1 and 2; and the bore of the hub is also increased beyond the cross-sectional diameter of the staff it is intended to receive.

The bore at the side of the hub, provided with the arcuate wall 14, is preferably provided with an offset intermediate of opposite ends of the hub 12, as shown at 15, see Figures 2 and 3; this 5 side wall of the bore tapering from the off-set or shoulder 15 toward the end of the hub having arcuate wall 14 as shown at 16, and tapering from the opposite end of the hub to the off-set or shoulder 15, as shown at 17, see Figure 2.

10 In Figure 4 I illustrate in perspective the locking means which cooperates with the sloping and shouldered wall of the bore. This locking means is shown in the nature of a key 18 of width corresponding to the transverse width of the bore so 15 as to be readily insertable into the bore and be disposed lengthwise of the shaft or staff 10, as shown in Figures 1 and 2.

The side of the key 18, which is to be disposed toward the staff 10, is preferably flat to correspond with the side of the non-circular staff 10; while the other side face of the key, namely the side 19 which is intended to be presented toward the curved wall 14 of the bore, is made arcuate to correspond with the wall of the bore in the 25 ratchet.

The key 18, at opposite ends, is provided with flanges 20 and 21 which preferably extend throughout the width of the key; the arcuate side 19 of the key 18 is shown tapering from the upper 30 or head flange 20 toward the bottom or toe flange 21, see Figures 2 and 4; the taper corresponding with the tapered portion 16 of the ratchet-bore.

The length of the key 18 from the bottom of head flange 20 is substantially the same as the 35 length of the hub of the ratchet; and the width of head flange 20 is such that it will overhang the arcuate wall 14 of the hub; while the toe flange 21 is adapted to engage beneath the shoulder 15 in the bore of the ratchet.

40 The thickness of the key 18, adjacent to head flange 20, is such that the key 18 may be in snug wedging relation with staff 10—if the latter has been forged to maximum dimensions—before the head flange 20 contacts with the curved wall 14 45 of the ratchet, while the toe flange 21 at that time is located beneath the off-set or shoulder 15 when the staff 10 has been inserted through the bore of the ratchet.

With the key 18 made as shown and described, 50 allowance is made for slight differences, either way, that may occur in the forged staff. It is apparent from the illustration in Figure 2 that in the event of some slight variance, namely a staff of somewhat less transverse dimensions or thickness, the key 18 may be driven farther into the hub-bore until a rigid wedging relation is effected.

With the one surface conforming to the contour of the adjacent wall of the bore and the other surface of the key conforming to the flat 60 surface of the contacting side of the staff, a very rigid and self-locking relation between staff and ratchet is obtained; at the same time a locking relation which may be adjusted to any slight differences that may occur in the casting of the ratchet and/or the forging of the staff.

65 With the key 18 provided with the flanges 20 and 21, loss of the key will be impossible if the staff 10 should work loose in the bore of the ratchet; the key being placed in firm locking relation by means of hammer-blows on the enlarged 70 or head-flange end of the key; and too far outward movement of the key in the direction of the head end will be prevented by the toe flange 21 coming in contact with the shoulder 15 in the wall of the ratchet.

In Figures 5 to 8, inclusive, I illustrate a modification wherein the invention is shown adapted to the locking of a ratchet on a staff or shaft of circular cross-section.

5 In this modification the ratchet 11 is identical with ratchet 11 previously described and shown in Figures 1 and 3, with one wall of the enlarged hub-end shown curved at 14, and this wall, intermediate of the ends of the hub, provided with an off-set or shoulder 15.

10 The ratchet 11 is shown mounted on a staff or shaft 22 of circular cross-section and therefore the locking key member 23 has both faces made arcuate. That is to say, the face which contacts with the arcuate wall 14 of the hub, like the face 15 19 of the key 18, made arcuate as is also the face 24 of key 23 which is intended to contact with the round surface of shaft 22. The key 24 is also provided on what may be termed its outer face with a head flange 20 at the larger end and a toe 20 flange 21 at the tapered end.

15 In order to lock the key member 23 to the round shaft 22 and to transmit rotative movement of the shaft to the ratchet—or vice versa—the inner or shaft engaging side 24 of the key 25 member 23 is shown with a slot 25 extending from end to end of the key. This slot is intended to accommodate a spline or bar 26 which is adapted to also extend lengthwise of a groove 27 formed in shaft 22; the groove 27 being made 30 of greater length than the length of the key 23 and of hub 12 so as to permit the bar 26 to be inserted after the shaft or staff 22 has been passed through the hub of the ratchet with key 23 inserted in the hub.

35 It is apparent from both constructions that accidental dissociation of the elements, or loss of the keys, is impossible even if the key should work loose because the toe flange 21 will engage beneath the shoulder 15 and prevent further 40 movement of the key in the direction of its head end. The parts can only be disassembled by withdrawing the shaft or staff, which can be done with the construction shown in Figure 5 after the bar 26 has been properly removed. As 45 is evident, by forcing the key in the direction of the toe flange 21 the main wall of this key not only forms firm wedging engagement with the sloping wall 16 but the toe flange 21 will also form wedging engagement with the tapered wall 50 on the other side of shoulder 15.

The invention has been set forth as particularly adapted to the ratchet of a brake-staff or dump car operating shaft, but it is apparent that it may be employed with shafts of different 55 cross-sectional configuration and modifications in the key may be made in keeping with the configuration of the shaft and the adjacent walls of the bore of the ratchet; such changes being possible without departing from the spirit of my 60 invention.

What I claim is:

1. Shaft and ratchet locking means comprising, in combination with a shaft, a ratchet having a hub provided with a shaft receiving bore, one 65 side wall whereof is off-set intermediate of the ends of the bore, and a key insertable in the hub-bore between the shaft and said off-set wall, said key having flanges at opposite ends, the flange at one end being adapted to engage beneath said off-set.

70 2. Shaft and ratchet locking means comprising, in combination with a shaft, a ratchet whose hub is provided with a shaft receiving bore of greater transverse dimensions than the thick- 75

ness of the shaft and having one wall provided with an off-set intermediate of the ends of the bore, said wall of the bore sloping from the off-set toward one end of the hub and sloping from 5 the other end of the hub toward said off-set, and a key adapted to be inserted in the bore and of length greater than the length of the first mentioned sloping portion of the bore and provided with flanges at both ends disposed laterally on the same side of the key, one flange being adapted to engage with the end of the hub while the other flange is adapted to engage with the shoulder in the bore.

3. Shaft and ratchet locking means comprising, in combination with a shaft, a ratchet provided with a shaft receiving bore of greater transverse dimensions than the thickness of the shaft and having one wall of the bore off-set intermediate of the ends, said wall sloping from 10 said off-set toward one end of the bore and sloping from the opposite end toward said off-set, and a key adapted to be inserted in the bore and of length greater than the length of the first mentioned sloping portion of the bore and

provided with flanges at opposite ends, one of said flanges being adapted to engage beneath the off-set in the wall of the bore, the key having a tapered side corresponding with said first mentioned sloping portion.

4. Shaft and ratchet locking means comprising, in combination with a shaft provided with a slotway, a ratchet provided with a shaft receiving bore of greater transverse dimensions than the thickness of the shaft with one wall 15 provided with a shoulder intermediate of the ends of the bore and the wall of the bore tapered from said shoulder toward one end of the bore, a key adapted to be inserted in the bore and of length greater than the length of the tapered 15 portion of the bore and provided with a flange disposed laterally from one side adapted to engage beneath said shoulder, said key on the side provided with the flange being tapered toward said flange while the opposite side of the key 20 is provided with a slot extending lengthwise thereof, and a spline insertable in said key bolt and slotway in the shaft.

VICTOR H. HARBERT.
